PLEAT PIN

Nicholas Murgolo, Uniondale, N. Y.

Application November 5, 1956, Serial No. 620,462

2 Claims. (Cl. 160—348)

This invention relates to a pleat pin for forming pleats in drapery and more particularly to pleat pins wherein the prongs are disposed in a non-planar manner.

It is an objective of this invention to provide a novel pleat pin for forming novel pleats in drapery.

It is another objective to provide a pleat pin, the prongs of which are fixedly disposed in a non-planar manner.

It is a further objective to provide a pleat pin of simple manufacture and construction.

These and other objectives of this invention will become apparent upon reading the following descriptive disclosure taken in conjunction with the accompanying drawing in which:

Fig. 1 is a perspective exploded view of a modification of the pleat pin with four prongs disposed in planar relationship and with the fifth prong disposed in front of the planarly disposed prongs and showing a clip detached from the base of the pin.

Fig. 2 is a side view of the modification of Fig. 1 showing swingable securing of the clip to the pin base.

Fig. 3 is a perspective view of another modification consisting of five pins having two pairs of parallel pins disposed in parallel planar relationship and the fifth pin disposed as the apex of a triangle formed by said pairs of parallel pins.

Fig. 4 is a side view of the pin of Fig. 3.

Fig. 5 is a front view of a drape having conventional drapery tape sewn thereon.

Fig. 6 is a front view of a box pleat formed by the pin of Fig. 1.

Fig. 7 is a front view of the box pleat formed by the pin of Figs. 1 and 2 showing the dimple effect created by the use of the clip.

Fig. 8 is a front view of the French pleat obtained when using the clip, said clip being shown in dotted outline.

Fig. 9 is a view taken on line 9—9 of Fig. 6.

Fig. 10 is a view taken on line 10—10 of Fig. 8.

Fig. 11 is a top edge view of a French pleat made by the use of the pleat pin of Fig. 3 showing back four prongs disposed in the consecutive pockets of the drapery tape and the front fifth apex prong unconfined.

Fig. 12 shows the manner of forming a box pleat with the pin of Fig. 11 and further shows the manner of disposing the prongs in the consecutive pockets of the drapery tape.

Fig. 13 is a perspective exploded view of a three prong modification of the pleat pin showing the clip disposed beneath the body of the pleat pin.

Fig. 14 is a side view of the pin of Fig. 13 showing the manner of attaching the clip to the pin and showing by an arrow the manner of movement of the attached pin to seize the drape disposed on the pin prongs.

Fig. 15 is a front view of the box pleat formed by the pin of Fig. 13 without the use of the clip.

Fig. 16 is a front view of the French pleat formed by the use of the clip.

2

Fig. 17 is a sectional view taken on line 17—17 of Fig. 15.

Fig. 18 is a sectional view taken on line 18—18 of Fig. 16 and showing the clip swung into seizure position

5 against the drape.

Fig. 19 is a perspective view of a further modification of the pleat pin, the four prongs being disposed in the form of a truncated pyramid, and

10 Fig. 20 is a top view of the pin of Fig. 19 showing a clip secured to the base of the pin.

According to this invention the pleat pin prongs are disposed in the form of a triangle (Figs. 1, 3 and 13) or a truncated triangle (Figs. 19 and 20). Preferably the pin is provided with a clip swingably secured to its base. The pin consists of at least three parallel prongs vertically disposed in a manner so that a top view of the prongs indicates a triangle or truncated triangle.

The pleat pin of this invention is operable without the use of a clip, but the use of a clip is preferred in order to give novel beautiful and enhanced effects to the drapes. In other words all the pin modifications may be provided with swingable clips secured to their respective base in order to obtain a dimple effect to a box pleat or to obtain a French pleat having a beautiful custom made appearance.

Turning to the modification of Figs. 1, 2 and 6 to 10 inclusive, the pleat pin consists of five elongated prongs and a hanger loop 31. As shown in Fig. 1 four of the prongs are disposed in a plane forming the base of a triangle and the fifth prong is disposed a suitable distance in front of this plane and forming the apex of the triangle. In other words, the pleat pin of this invention has its prongs disposed in a non-planar or tri-dimensional manner with consequent effect on the drapery used therewith.

The pin of Fig. 1 is formed from an inner rod 32 bent into a U-shaped configuration having a base 33 and an outer rod 34 having a U-shaped configuration and a base 35. The prongs of both rods 32 and 34 are parallel to one another. The base 33 of rod 32 is suitably short and the prongs 30 of rod 32 are slightly shorter than the prongs 30W of rod 34. The base 35 of rod 34 is suitably long so that rod base 33 may be placed on rod base 35 with the respective prongs 30 and 30W of both rods disposed in planar manner.

45 The base 33 is then soldered or spot welded to base 35 giving a planar element having equally spaced-apart prongs disposed in parallel planar relationship. The top of prongs 30 and 30W (Fig. 1) are disposed in a straight line. Other manners of obtaining four united parallel prongs in planar relationship are possible since the inner two prongs 30 of the four planar prongs may be individual unbent rods (not shown) separately secured to the rod base 35.

55 The hanger loop 31 is suitably bent to be disposed about a drapery holding rod and is of unitary construction with the apex prong 30X. In other words, the apex prong 30X is provided with and integral to base 36 and integral to loop 31. The base 36 is secured as by welding or soldering beneath rod 35 at a right angle thereto and in the middle thereof. The apex prong 30X of suitable length is disposed a suitable distance in front of the plane formed by the four prongs constituting the base of the triangle. The tips of all the prongs 30, 30W and 30X are disposed in a horizontal plane.

60 A unitary wire clip 37 also of a generally U-shaped construction is provided with a base 38 and parallel sides 39. The extension of sides 39 are reversed upon themselves to form knees 40 and extensions 41. The extensions 41 are themselves given a reversed securing loop 42 adapted to swingably engage rod base 35 (Fig. 2). The sides 39 of the clip 37 are suitably spaced apart to

suitably clamp the drape disposed at the base of the pleat pin.

The pleat pin of Fig. 1 and that of Fig. 2 forms a box pleat having the appearance shown in Fig. 6 and a dimple box pleat having the appearance shown in Fig. 7.

To obtain the box pleat of Fig. 6 the four planar prongs 30 and 30W and the apex prong are disposed in the consecutive prong receiving sewn pockets 43 (Fig. 9) of a conventional drapery tape 44, which tape is sewn adjacent to the top of the drape 45.

Fig. 7 shows the presence of a dimple 46 formed by clamping the clip 37 into position against drape 45. For purposes of clarity the clip is not shown in dotted outline in Fig. 7 but is shown in Fig. 8 with respect to formation of a French pleat with the pleat pin of Fig. 1.

As shown in Fig. 10, the apex prong 30X is not inserted in a pocket to form the French pleat with the pin of Fig. 1, rather the four planar prongs 30 and 30W are consecutively disposed in the consecutive pockets of the tape 44.

Turning now to the modification of Figs. 3, 4, 11 and 12 the prongs are disposed in the form of a triangle having a pair of planes of two prongs each, the planes being disposed in parallel relationship, and an apex prong. In this modification a rear U-shaped rod element 48 having suitably spaced-apart prongs 30A and an intermediate U-shaped rod element 49 having suitably spaced-apart prongs 30B are suitably and fixedly unitary element consisting of the hanger loop 31 (Fig. 3) base 50 and the apex prong 30C. As shown in Fig. 4 the tips of all the prongs are disposed in a horizontal plane.

Fig. 11 shows the manner of inserting four of the pins of the pyramidal configuration pin of Fig. 3 in the consecutive pockets of a drapery tape to obtain a French pleat, the use of the clip 37 being preferred to obtain the especially pleasing appearance of a custom made pleat. In obtaining such a French pleat the apex prong 30C is not inserted in a tape pocket.

Where the apex prong 30C of the modification of Fig. 3 is inserted into a consecutive tape pocket, the result is a box pleat (Fig. 12). The front view of this box pleat is strikingly similar to that of the box pleat of Fig. 6. Also a dimple pleat (Fig. 7) is obtained with the modification of Fig. 3 when the clip 37 is swung into clamped relationship to the drape 45.

A further modification of this invention is the three prong pleat pin of Fig. 13. In this pin only one U-shaped rod element 51 is used. The height of the prongs 30M of element 51 is such that the tips of these prongs lie in the same plane as the tip of the apex prong 30N. The modification of Fig. 13 is further modified to show a hanger loop in circular form adapted to receive a round drapery holding rod. This modification of Fig. 3 is preferably combined with the clip 37 to obtain custom-like pleats. Figs. 15 and 17 show the form of the box pleat obtained with the three prong pin, Fig. 17 showing the apex pin as confined in a tape pocket. Fig. 16 shows the French pleat obtained by inserting the three prongs

in consecutive pockets of a tape and by employing a clip 37 to obtain a custom pleat effect to the French pleat.

A further modification of this invention is shown in Figs. 19 and 20. The configuration of the pleat pin of this modification is that of a truncated pyramid since the apex prong is absent. In other words, the modification of Figs. 19 and 20 is in effect the pin of Fig. 3 with the apex prong cut off. This modification is used to obtain a French pleat of custom-made appearance especially when combined with a clip 37 (Fig. 20) to clamp the drape to the pin.

For purposes of clarity the section views 9, 10, 11, 12, 17 and 18 of the pleat pin, shows the drapery in perspective in order to show the type of pleat produced. Furthermore, the tape is indicated diagrammatically in these views, showing only the tape pockets secured to the drapery. The detail structure of the conventional tape used and of the conventional manner of sewing it to the drapery is shown in Fig. 5.

Having described the pin, those skilled in the art will become aware of still further modifications of this invention, but all these obvious modifications within the scope of this invention are intended to be covered by the claims herein.

I claim:

1. A pleat former five prong pin for drapery having suitable vertical pin receiving pockets thereon comprising a pair of U-shaped rod members, each U-shaped member having a pair of vertical prongs and a horizontal base, one of said U-shaped rod members having a shorter base between the prongs than the other, said U-shaped rod members being disposed relative to one another in parallel planar relationship, a substantially U-shaped support element having a rear hanger loop and a front apex prong, said support element having a horizontal base secured fixedly and at a right angle to the pair of bases of said rod elements, the five prongs of said members and support element being disposed in a triangular configuration.

2. The pin of claim 1 comprising a clip hingedly secured to the larger horizontal base of the respective U-shaped member and adjacent the vertical prongs thereof, said hinge pin consisting of a substantially U-shaped member having identical legs, having identical integral leg extensions disposed over the legs, said extensions having integral identical loops disposed over said leg extensions, said loops being secured to said larger horizontal base of the respective rod member.
